BUCKLE

Morris Weiss, Far Rockaway, N. Y., assignor to
Liberty Die & Button Mould Co., Inc., New
York, N. Y., a corporation of New York

Application November 3, 1933, Serial No. 696,479

1 Claim. (Cl. 24—178)

This invention relates to improvements in buckles such as employed on wearing apparel and has particular reference to the cross bar construction therefor.

5 It has been heretofore known to make buckles of two metallic plate members each of which is provided with a channelled cross bar, and to interengage said plate members so that the cross bar of one plate is nested within that of the other in order to reinforce the structure against strains to which it is subjected when in use.

An object of the present invention is to provide an improved buckle of practical construction in which the cost of production as compared with 15 known structures, is materially lessened by the elimination of the cross bar of one of the two plate members of the buckle, and the cross bar of the other member stiffened against strains by the attachment thereto of a separate reinforcing element.

Another object is to provide a buckle of simple construction wherein the cross bar thereof is made to at least partially embrace a reinforcing rod that is co-extensive therewith so as to hold 25 said rod in rigid position to thereby strengthen the cross bar.

The above and other objects will appear more clearly from the following detailed description when taken in connection with the accompanying 30 drawing which illustrates a preferred embodiment of the inventive idea.

In the drawing:

Figure 1 is a front elevation of a buckle constructed in accordance with the invention.

35 Figure 2 is a rear elevation thereof.

Figure 3 is a plan view of the inner side of the front plate member forming a part of the buckle.

Figure 4 is a similar view of the rear plate 40 member.

Figure 5 is a section on the line 5—5 of Figure 1, and

Figure 6 is a section on the line 6—6 of Figure 1.

45 In the preferred form of the invention illustrated herein, the buckle is shown as comprising the cooperating front and rear plates 7 and 8, respectively, both of which are stamped from any suitable sheet metal. The plates are shown as 50 rectangular in formation, but it will of course be understood that they may be made to assume any desired configuration.

The front plate 7 is provided around its entire outer edge with a lateral flange 9 and centrally 55 thereof there is formed an opening 10 which

also has its periphery provided with a flange 11 similar to the flange 9. The opening 10 is divided medially of two of its opposed edges by a cross bar 12 of channelled formation so as to include two side walls or flanges 13 which add rigidity 60 to the structure. Due to the strains to which the cross bar is subjected when in use it is desirable to additionally reinforce the cross bar. In accordance with the present invention, this is accomplished by the use of a reinforcing wire 65 rod 14 which is introduced into the channel of the cross bar 12 and securely held therein by bending the side walls 13 of said bar inwardly toward each other and into contact with the rod 14 so that the bar will effect a three-point 70 contact therewith as shown in Figure 5. The rod 14 is of a length to be co-extensive with the cross bar and its ends project slightly beyond the ends of said bar into overlapping relation to adjacent portions of the plate 7 so as to additionally reinforce the junction point between said 75 ends of the bar and the edges of the opening 10 where the flange 11 is cut away to accommodate said projecting ends of the rod. At an intermediate point of the bar 12 the width of 80 the same may be reduced by crimping the material as indicated at 15 so as to form a bearing for the customary pivoted tongue 16 of the buckle.

The rear plate 8 of the buckle body is of the 85 same configuration as the plate 7 but slightly smaller in size, and is provided around its marginal edge with a flange 17 which is adapted to fit within the flange 9 of the plate 7 when the two plates are assembled. The plate 8 is also 90 provided with a central opening 18 slightly larger than the opening 10 and bordered by the flange 19 designed to receive within its confines the flange 11 of the plate 7, the flange 19 being provided with opposed notches 20 into which the 95 ends of the cross bar 12 are fitted.

It is desirable in buckles of this character to enhance the ornamental appearance thereof by providing the outer plate 7 with a covering of fabric 21. This covering is attached in its operative 100 position and securely held therein when the two plates 7 and 8 are assembled. To this end the edges of the covering 21 are first folded over the flanges 9 and 11 of the plate 7, as indicated at 22 in Figure 5, and the plate 8 is then 105 introduced into the plate 7 with the flanges 17 and 19 engaging the edge portions of the covering 21 and wedging the same between said flanges and the adjacent flanges 9 and 11 of the plate 7, thereby maintaining the covering 21 in a 110

stretched condition over the outer face of the front plate 7.

What is claimed is:

In a buckle, a body comprising two plate members formed of sheet metal and each having a central opening, the marginal edges of said plates and those of said openings being provided with interengaging flanges, a bar of channelled forma-

tion extending across the opening of only one of said plates, and a reinforcing rod rigidly held in the channel of said bar by contact with the walls thereof and having its ends projecting beyond the ends of said bar into overlapping relation with adjacent portions of the plate carrying said bar.
